OSCAR HAMMEL, OF JERSEY CITY, NEW JERSEY.

Letters Patent No. 65,808, dated June 18, 1867.

IMPROVEMENT IN ELECTRIC APPARATUS FOR LIGHTING GAS ENGINES.

The Schedule referred to in these Letters Patent and making part of the same.

TO ALL WHOM IT MAY CONCERN:

Be it known that I, OSCAR HAMMEL, of Jersey City, in the county of Hudson, and State of New Jersey, have invented a new and improved Electric Apparatus for Gas Engines; and I do hereby declare that the following is a full, clear, and exact description thereof, which will enable those skilled in the art to make and use the same, reference being had to the accompanying drawing, forming part of this specification, in which—

Figure 1 represents a plan or top view of this invention partly in section.

Figure 2 is a sectional front elevation of the same.

Figure 3 is a transverse vertical section of the same.

The remaining figures are details and modifications, which will be referred to as the description progresses.

Similar letters of reference in these views indicate corresponding parts.

This invention relates to an electric apparatus, which is intended to be attached to or connected with the cylinder of a gas engine, and which is so arranged that, by its action, the explosion of the gas in said cylinder is effected at the proper intervals in a safe, sure, and economical manner.

The invention consists in a pendulum-switch, which connects with one pole of a battery, and to which an oscillating motion is imparted by a reciprocating slide, or by any other suitable means, in such a manner that the same is alternately brought in contact with two studs, connecting with the inflamers at the opposite ends of the working cylinder, and that by this motion of the pendulum-switch the gas in said cylinder is exploded at the proper intervals. The intensity of the current is increased by an electro-magnetic hammer, and by a combination helix or coil, which is applied in combination with the battery, and the vibrating motion of said electro-magnetic hammer is produced by a serrated bar or rack, attached to the slide or other part, which imparts motion to the pendulum-switch in such a manner that a powerful spark is obtained with a comparatively weak battery and with a small expenditure of acid, the whole apparatus being so arranged that it operates just at the time when the sparks are required, and that all waste of electricity and of the materials required to produce the same is avoided.

A represents a bed-plate, which is made of cast iron or any other suitable material, and which is intended to be attached to the working cylinder of a gas engine, or which may be secured in any convenient spot close to or in the neighborhood of said cylinder. One end of this bed-plate serves to support the battery B, which is constructed as follows: The positive pole-plates P are made of circular grates, cast of zinc, as shown in Figure 3, and for the negative poles N I use one or two series of spirals of fine silver wire, or copper wire plated with silver or platina, according to Simee's principle, and connected together by stout arms of copper, as shown particularly in Figure 4. Said arms radiate from the inner ends of cylinders a of copper or other metal, which are in metallic contact with rails b b*, as will be presently more fully explained. Through the cylinders a, and insulated from the same by disks c of gutta percha or other suitable material, pass the tubes or rods d, which support the positive pole-plates P, and which are in metallic contact with the rails b b*. The rails b b* and b' b'* are secured to a cross, e, which is made of wood or other non-conductor of electricity, and from which the positive and negative plates P and N are suspended. The rails b and b' are in metallic contact with the central stud f, to which is also attached a handle, for the purpose of raising the plates out of the acid; and by these means the positive pole of one cup connects with the negative pole of the other cup. The rails b* and b'* are in metallic contact with studs g g', which, when the apparatus is in operation, rest upon metal columns h h', and the lower ends of which may be formed into points, so that they will drop into corresponding cavities in the top ends of the columns, and thereby the cross with the pole-plates will be prevented from being displaced accidentally. When the battery is not used, the cross is raised and a stop, i, of wood or any other suitable material is put under the same, so that the zinc plates are lifted out of the acid and the action of the battery ceases. The columns h h' connect each with one of the ends 10 and 11 of the main wire of the coil or helix C. This helix is enclosed in a box, D, and it consists of two or more hollow glass rollers j, on which is wound a fine induction-wire of copper. This induction-wire is covered by glass tubes k, which are secured in place by means of beeswax and rosin. On the outer ends of the glass rollers j are mounted disks l of well-varnished wood or other suitable insulating material, which are perforated with holes, through which the ends of the wires pass, as shown in fig. 1 of the drawing, and their inner ends are provided with flanges l', also perforated with holes, through

which the wires pass. This main wire is wound on the glass tubes *k*, and it is covered by an insulated layer of varnished paper or other suitable material, on which is wound a fine iron wire, well varnished, and covered with silk or wool; or, instead of using fine covered iron wire, thick uncovered iron wire, well coated with varnish, can be used. This wire is wound so that all the layers run in one and the same direction, and it serves to increase the power of the induction the same as a bunch of metal rods introduced into the interior of the hollow glass rollers *j*. After the wire is properly wound, and the bunch of metal rods adjusted in position, the intervening flanges *l*' are well covered with melted wax or rosin, and firmly pressed together, and thereby the whole coil is united, and the transit of the spark from one to the other of the wires passing out through the holes in said flanges is prevented.

The ends of the wires are combined, viz; those of the induction-wire of copper, and also those of the fine covered iron wire, when such is used, and one end of the combined induction-wires is brought in metallic contact with the pendulum-switch *G*, and the other end with the engine, or if covered iron wire is used, the second end of the combined induction-wires is connected with one end of said iron wire, the other end of which connects with the engine. The ends 12 and 13 of the main wire, passing out between the intervening flanges *l*', are in metallic contact, one with the electric hammer *E*, and the other with the anvil *F*, (see fig. 3.) The electric hammer *E* is secured to one or two spring-arms *m*, which retain the same in such a position that its lower face stands a little above the surface of the anvil, and its upper face a little below the point of a set-screw, *n*, which screws into a standard, *o*, and which can be adjusted so as to bring its point to the desired distance from the upper face of the hammer. The faces of the hammer, and also that of the anvil, are covered with disks of platina, whereby the electric action thereof is materially improved. From the electric hammer rises a point or triangular saddle, *p*, and a serrated bar or rack, *q*, which is attached to a reciprocating slide, *H*, sweeps over this saddle, and imparts to the hammer a rapid vibrating motion, whereby the faces of the same are alternately brought in contact with the anvil and with the point of the set-screw *n*, and the required interruptions of the current are effected. From the top of the slide rises a standard, *r*, and as said slide reciprocates, the face of this standard bears against a spring, *s*, which is connected to the pendulum-switch *G*. This switch is suspended from a pin, *t*, which projects from the box *D*, and from its top projects an arm, *u*, which, when the pendulum is left to follow its inherent gravity, stands in the middle between two metallic studs *I* *I*. These studs connect by suitable wires with inflamers at the opposite ends of the working cylinder, and as the slide *H* reciprocates, the arm *u* is alternately brought in contact with one and then with the other of said studs, and thereby the circuit of the induced current is alternately closed, and the gas in the cylinder is ignited at the proper intervals. The arm *u* is held in contact with either of the studs *I*, just as long as the face of the standard *r* bears against the springs *s* of the switch, and as soon as this standard has passed the spring, and when the toothed rack has passed the saddle *p*, the pendulum-switch returns to its original position and the circuit is broken, and consequently the electric spark is used only at the moment when it is needed, and no electricity is wasted.

It is obvious that various modifications of the coil, and particularly of the means employed for producing the vibrating motion of the electric hammer, can be devised. In Figures 7 and 8 I have represented modifications of the coil, fig. 8 being a coil with tapering ends, and fig. 7 a coil similar to that represented in fig. 1, but composed of three sections, and if desired the number of sections may be still further increased. Instead of the slide, a vibrating cam might be employed, such as shown in Figure 9, or a vibrating segment, such as shown in Figure 10. A portion of the surface of the cam and also of the segment is serrated to act against the triangular saddle of the electric hammer, and the cam may be so arranged that its two horns bear against the spring of the pendulum-switch, and keep the same in contact with one of the studs *I* for the desired length of time. The reciprocating motion of the slide or the vibrating motion of the cam or segment is produced by an eccentric or rock-shaft from the engine, or by any other suitable means.

What I claim as new, and desire to secure by Letters Patent, is—

1. The arrangement of the battery *B*, coil *C*, pendulum-switch *G*, and electric hammer *E*, all constructed and operating substantially as and for the purpose set forth.
2. The pendulum-switch *G*, in combination with the slide *H*, or its equivalent, constructed and operating substantially as and for the purpose described.
3. The electric hammer *E*, in combination with the slide *H*, or its equivalent, and with the pendulum-switch *G*, constructed and operating substantially as and for the purpose set forth.
4. The saddle *p* on the electric hammer *E*, in combination with the serrated bar *q* on the slide *H*, or its equivalent, constructed and operating substantially as and for the purpose described.

OSCAR HAMMEL.
